UNITED STATES PATENT OFFICE.

BARTON PICKERING, OF DAYTON, OHIO.

TELEPHONE.

SPECIFICATION forming part of Letters Patent No. 511,358, dated December 26, 1893.

Application filed January 29, 1881. Serial No. 24,990. (No model.)

To all whom it may concern:

Be it known that I, BARTON PICKERING, a citizen of the United States, residing at Dayton, in the county of Montgomery and State 5 of Ohio, have invented a certain new and useful Improvement in a Combined Microphone, Electric Alarm, and Telephone; and I do hereby declare that the following is a full, clear, and exact description of the invention, which 10 will enable others skilled in the art to which it appertains to make and use the same, reference being had to the accompanying drawings, and to the letters and numerals of reference marked thereon, which form a part of 15 this specification.

My invention relates to improvements in a combined microphone, electric-alarm and telephone.

The objects are to sound an alarm, to transmit and receive vocal messages or other sounds by voltaic and magnetic agencies. I attain these objects by the mechanism illustrated in the accompanying drawings, in which—

Figure 1 is a central longitudinal section 25 and a part on line 1 1, Fig. 2, of the instrument with portions cut away. Fig. 2, is a top view or plan of the instrument with the front of the case removed. Fig. 3, is a section of the switches and the back of the case. Fig. 4, 30 is a diaphragm and elastic ring. Fig. 5, is a diagram of the electric circuits. Fig. 6, is a top view of the frame. Fig. 7 is a transverse section of the telephone case and contiguous parts, on line 7 Fig. 1.

Similar letters and numerals designate like 35 parts throughout the several views.

A, is a quadrangular case with a projecting back, and A' is the front of the case, which has an orifice serving as a mouth-piece, and 40 an orifice for the adjusting screw.

R is a metallic frame, the front end supports the magnet and induction coil, H, the central portion of the helices U, and the rounded projection the bell N. This frame 45 is securely fastened to the back of case by a screw.

The permanent magnet C, with parallel poles is bolted to the frame R, and to the outer pole is bolted the telephone case E, the 50 top end of which is notched for the reception of the spring contact r', and the armature lever r, and between which parts and the mag-

net, are small insulating substances, and between which said parts are securely held. The lower end of the case has a circular orifice for the reception of the plug 7, and like ledges are formed on the face of said plug and in the case, for a bearing for the vibrating plate 3; and from the recess of the case is a small orifice opening through opposite of 55 the mouth-piece. The case is held to the outer pole of the magnet by the bolts m, m'. Both poles of the magnet are pierced directly opposite, the outer to receive the threaded hollow electro-magnet 2, and the inner the 60 electro-magnet 6. The former electro-magnet is surrounded by the helix 4, and the latter by the helix 8.

D is a bar held in notches of the sides of the case and against the back, and the left 70 end has a button on which to hang a telephone, and the right end is connected to the switch F by a pin. Being moved by the switch a telephone can only be hung on the button of this bar, when the switch is in position for a call or signal.

The switch J, has a circular rim at its center, which has a bearing in the wood of the back. Within this rim is placed the insulating button J', and over this is placed the switch 80 F, and these several parts are held to the back by the bolt x. The switch J has contact with the metallic posts O⁴ and O⁵; and the switch F, has contacts with the posts O, O', O², O³, O⁶ and O⁷. Both switches are provided with projections to handle them.

The bolt m, supports the adjusting spring 1, which bears against the carbon button 5 and which bears against the diaphragm 3. To the fixed end of the adjusting spring is 90 attached one end of the primary coil of the induction helix H. S is the adjusting screw, by which the pressure of the carbon button on the diaphragm is regulated. It is held in the wood of case E and passes through an 95 orifice of the magnet without contact therewith.

L, L', are binding screws for the line wires, B, B', for the local battery wires, and T, T', for the telephone wires. The dotted lines 100 Fig. 2, show the wire connections in the back, and the curved lines the visible wire connections.

At Fig. 5 are shown diagrammatically the

several electric circuits, B² local battery and B³ battery at distant station, *St.* The microphonic circuit is thus, local battery B², post O⁶, switch F, post O', telephone T², helix 8—5 which may be omitted—helix 4, diaphragm 3, carbon connection 5, adjusting spring 1, primary coil P, station battery B³ over line L², back to local battery. Identical instruments must be used at both ends of the line. The 10 terminals of the secondary coil of the induction helix H, are connected to the line and to the primary coil.

The telephone T², may be left out of the circuit; then the electric circuit would be 15 from post O' to helix 8, and then to helix 4; or direct from post O', to helix 4, as indicated by the curved dotted line. The helix 4, in its relation to the hollow electro-magnet 2 and the diaphragm 3, is made to vibrate in 20 unison with a magnetic wave from a distant telephone, or the undulatory wave of a voltaic current from a distant microphone, and when the ear is placed against the mouth-piece of the instrument, the initial sounds 25 are distinctly heard as they are transmitted. Inasmuch as carbon is of low conductivity; a circuit can be formed by a wire connecting the diaphragm with post O⁴ and over switch J, to post O⁵, thence to line wire L³. This 30 cuts out the microphone parts and leaves a metallic circuit, which is advantageous in transmitting over long lines, and is likewise advantageous in transmitting and receiving solely by the magneto-telephone of the instrument. This electric circuit is identical 35 in other respects with that heretofore described. The three parallel lines L³, are but one wire having distinct terminals. A spiral coil of bonnet wire 9—see Fig. 4—laid against 40 the outer surface of the diaphragm forms an elastic bearing for said diaphragm, and the free end, extending beyond the bearing surface, tends to arrest vibrations of said part.

For transmission of speech a small piece of 45 carbon backed by a non-magnetic wire is best, and may be insulated from the inclosing electro-magnet, but for the transmission of musical sounds the carbon should be dispensed with and a small wire substituted therefor, to 50 produce the best results. When the instrument is operated in connection with batteries, the voltaic forces, are amplified by the magnetic wave of the telephone, and when the battery circuits are broken, the transmission 55 is alone by the induced current of the electro-magnet or magnets, resulting from the vibrations of the diaphragm.

The diaphragm and the carbon button form 60 the electrodes where the variation of the circuit occurs, and one end of the primary coil of the induction helix may be attached to bolt m', or attached to the adjusting spring, which may be insulated from the magnet or not, as it is only requisite for the current to 65 traverse the carbon.

On the frame R are mounted the helices U, and over the poles of which are held the ar-

mature lever r, which carries the clapper v, and over said lever is the spring contact r'. When the voltaic current traverses the helices the armature is drawn down causing the clapper to strike the bell N; this movement breaks the circuit, and the clapper rebounds and renews the circuit, thereby producing a continuous vibratory movement of said clapper in contact with said bell. The ringing of this signal bell is caused by a current from a distant battery, and the electric circuit is as follows: battery B³, spring contact r', armature lever r, helices U, post O, switch F, 80 post O³ to opposite pole of said battery. To ring a signal bell at a distant station, the electric circuit is as follows: local battery B², post O', switch F, post O², line L³, signal bell, and line L² to opposite pole of said battery. 85

At Fig. 4, is shown the diaphragm 3, on which is shown a spiral coil of bonnet wire 9,—that is, iron wire surrounded with cotton thread—the inner end of said coil extending beyond the case bearing, which is indicated 90 by a circular dotted line. The outer part forms a flexible bearing for the plate or diaphragm, and the inner end tends to arrest the vibrations of said diaphragm. This flexible coil is preferably placed on the surface of the 95 diaphragm next to the mouth-piece.

When in use the instrument is attached to the wall of a room and the back A, is indispensable, but the instrument is operative without the inclosing part of the case and 100 a suitable mouth-piece may be attached directly to the telephone case.

Having thus fully described my invention, what I claim, and desire to secure by Letters Patent, is—

1. The case E provided with a notch at its rear end, the permanent magnet C these supporting parts in combination with the binding bolt M, armature spring r with clapper attached, contact spring r', the latter two held in said notch, metallic frame R, helices U supported on said frame, and bell N held on a standard of said frame, and a charged electric circuit, substantially as and for the purpose specified.

2. The case E provided with an orifice, the plug 7 to fill said orifice, in combination with the diaphragm 3 held on ledges of said case and plug, the permanent magnet C provided with the hollow electro-magnet 2, the carbon 120 button 5, the adjusting spring 1, the latter two having metallic connection and a charged electric circuit for microphonic transmission, substantially as described.

3. The case E with plug 7 in combination 125 with the diaphragm 3, permanent magnet C with electro-magnets 2 and 6 mounted thereon, carbon button 5 with metallic stem, the adjusting spring 1, the induction coil H, and a charged electric circuit for microphonic 130 transmission, substantially as described.

4. A telephonic instrument comprising the permanent magnet C with the electro-magnet 2 and its helix 4 mounted in its pole, with the

- case E and its plug 7 bound to said magnet, substantially as described.
5. The combination of the telephone provided with a central orifice through the pole of its magnet and the microphone having a vibrating plate in common, to receive vibratory action through air disturbances, and an adjustable contact with said plate producing partial disruptions with a charged electric circuit, and adapted to the transmission of messages by concerted action, substantially as described.
10. The combination of the switch F, the pins or terminals O¹, O², O³, O, O⁷, O⁶ for the several circuits the bar D attached at one end to said switch and button for the suspension of a telephone on the other, and the inclosing case A, substantially as described.
15. The magneto-telephone comprising the case with orifice in the front surface, a bearing surface for the diaphragm, and a circular orifice through the back in combination with the plug, having a bearing surface and a central orifice, the magnet with an electro-magnet attached to its end, the induction coil and the diaphragm, and means to unite said case and magnet, to maintain the position of said plug against the edge of said diaphragm, and with suitable electric conductors, substantially as described.
20. In a combined telephone, microphone and alarm, the frame R provided with lugs for the support of the induction coil of the microphone, a lug for the support of the bell coils, post for the bell and bearing for the support of the permanent magnet, substantially as described.
25. In a combined telephone and microphone having but a single vibrating diaphragm, the bonnet-wire coil as a bearing for the under edge of said diaphragm, to give greater flexibility of movement, substantially as described.
30. In a combined telephone, microphone and alarm the frame R provided with lugs for the support of the induction coil of the microphone, a lug for the support of the bell coils, post for the bell and bearing for the support of the permanent magnet, substantially as described.
35. In a combined telephone and microphone having but a single vibrating diaphragm, the bonnet-wire coil as a bearing for the under edge of said diaphragm, to give greater flexibility of movement, substantially as described.

support of the permanent magnet, substantially as described.

9. In a combined telephone and microphone having but a single vibrating diaphragm, the bonnet-wire coil as a bearing for the under edge of said diaphragm, to give greater flexibility of movement, substantially as described.

10. In a combined telephone, microphone and alarm the frame R provided with lugs for the support of the induction coil of the microphone, a lug for the support of the bell coils, post for the bell and bearing for the support of the permanent magnet, substantially as described.

11. The magneto-telephone comprising the case with orifice in the front surface, a bearing surface for the diaphragm and a circular orifice extending through the back in combination with the plug having a bearing surface and a central orifice, the magnet with an electro-magnet attached to its end, the induction coil and diaphragm, and means to unite said case and magnet to maintain the position of said plug against the edge of said diaphragm, and with suitable conductors, substantially as set forth.

12. In a combined telephone and microphone having but a single vibrating diaphragm, the bonnet-wire coil as a bearing for the under edge of said diaphragm, to give greater flexibility of movement, substantially as set forth.
